CAP APPLYING APPARATUS

Milo Burnell, Decatur, Ill., assignor to Crown Cork Specialty Corporation, Decatur, Ill., a corporation of Illinois

Application February 11, 1946, Serial No. 646,840

6 Claims. (Cl. 226—81)

1

The present invention relates to cap applying apparatus and, more particularly, to an apparatus for placing a cap in a desired position with respect to the circumference of a container.

The invention is particularly useful in applying caps similar to those disclosed in Williams Patent No. 1,743,945, issued January 14, 1930, and Williams Patent No. 1,214,734, issued February 6, 1917.

A cap of the type disclosed in the two above-mentioned Williams patents includes a top sealing gasket, and a skirt which is contractable by downward movement of a pivoted locking lever to enable the cap to be firmly clamped upon a container mouth. Before such a cap is applied to a container, the locking lever is in upward or non-locking position. After the cap has been loosely applied to the container, it is forced straight down upon the container to bring the gasket into sealing relation with the container mouth. Then the locking lever is swung downwardly and outwardly through substantially 180° so that it will extend downwardly from the cap. One type of apparatus for applying such caps, forcing them to sealed position, and then moving the locking levers to locked position is disclosed in Mair Patents Nos. 2,351,348 and 2,351,349, both issued June 13, 1944.

When caps of the above-mentioned structure are applied to bottles which are not circular in horizontal section, for example, bottles which are substantially flat on two sides, as is the case with bottles which are elliptical in cross-section, it is desirable to have the locking lever lie along a vertical line which intersects a flat wall of the bottle. Having the locking lever positioned at this point enables it to be more readily operated by the capping machine and the subsequent consumer. In any event, the positioning of the locking lever at a uniform point on each container handled greatly improves the appearance of a group of the sealed bottles or other containers.

It is usually desirable to move a bottle including two substantially flat sides through a capping machine with the flat walls extending parallel to the line of movement of the bottle so that the greatest width of the bottle will thereby coincide with its direction of movement. In this way, the possibilities of the bottle falling forward or backward are minimized. However, if flat sided bottles move along a conveyor in this manner and if the locking lever of each cap is to extend down toward a flat side of the bottle, it has heretofore been necessary to supply the caps to the bottles from a cap chute in which each cap has its lock-

ing lever at one side of the chute. By this prior practice, the cap was removed from the cap chute with the locking lever already aligned with the desired flat side of the bottle.

One important difficulty with the cap feeding system described in the preceding paragraph was that when the locking levers were positioned at one side of the chute, the caps jammed in the chute. This is largely due to the fact that with the weight of the locking levers at one side of the chute, the lower rims of adjacent caps would overlap in the chute.

Generally speaking, the present invention obviates this cap feeding difficulty by moving the caps downwardly in the chute with their locking levers at the trailing or uppermost portion of the cap and then placing the locking levers in the proper position on the bottle by rotating each cap with respect to the bottle. With the cap locking lever thereby lying along a line intersecting a flat side of the bottle, the cap is then forced downwardly to sealed position and locked.

An important object of the invention is to provide an apparatus for placing a cap in a desired position circumferentially of a container.

A further important object of the invention is to provide an apparatus for placing a cap in a desired position circumferentially with respect to a container, and which apparatus is extremely simple, particularly in that it requires no power-driven or automatically actuated parts.

It has heretofore been usual to rotate a screw cap to a sealed position upon a container. However, the mechanisms used for this purpose are not designed to position the cap at any particular point circumferentially of a container. In addition, when a threaded cap is rotated circumferentially of a container, it is also moved axially of the container.

Other objects and advantages of the invention are disclosed in the following specification and accompanying drawings wherein:

Figure 1 is a front elevation of a cap applying and sealing apparatus including the mechanism of the present invention, portions being broken away.

Figure 2 is a top view of the structure shown in Figure 1, with the cap turning element in cap receiving position.

Figure 3 is a fragmentary view similar to Figure 1 and with a portion broken away to show the cap rotating mechanism turned approximately 60° from the position shown in Figure 2, and

Figure 4 is a top view of the Figure 1 structure

but with the cap rotating element in the position of Figure 3.

The drawings illustrate a cap applying and sealing apparatus for caps C provided with locking levers L, the apparatus being similar to that disclosed in the above-mentioned Mair patents but with the cap turning mechanism of the present invention interposed between the cap applying chute and the sealing head of the patent structures.

Referring to Figure 1, the numeral 10 designates an endless infeed conveyor to move an uninterrupted line of bottles or other containers 11 including substantially flat sides 11a beneath a cap applying chute 12. A bottle 11 will engage the forward portion of the skirt of the lowermost cap C and the cap will drop to a horizontal position upon the bottle mouth. The bottle will then carry the cap through a cap turning element 13 which will rotate the cap as hereinafter described. While the cap is still engaged by the element 13 the bottle will move on to a stationary plate 14 having its upper surface flush with the upper run of the conveyor 10. When the bottle is positioned on the plate 14 it will be pushed beneath the sealing head 15 by the next succeeding bottle and the line of contacting bottles on the conveyor 10. As the bottle moves beneath the sealing head 15, its neck will strike a trip 16 which operates the sealing head 15 as described in the said Mair patents to cause the head to descend, thereby moving the cap downwardly to sealed position upon the container. A shoe 17 forming a part of the sealing head 15 descends immediately thereafter to move the locking lever L of the cap from the upstanding position illustrated in Figure 3 so that the locking lever will extend downwardly from the cap. After the sealing and locking elements have raised through the actuation of controls described in said Mair patents, the succeeding bottles will push the sealed bottle onto the outfeed conveyor 18 which will carry it from the apparatus.

The cap chute 12 is of generally inverted U-shaped form in that it includes a bottom wall 20 and two upstanding side walls 21. Each side wall 21 includes an inwardly extending flange 22 at its upper end, the inner and opposed edges 22 of the top flanges 22 thereby defining a slot 23 between them. An attendant will place caps of the type shown in said Williams patents in the upper end of the chute 12 with the locking levers extending upwardly as illustrated in Figure 1, i. e., in unlocked position, and with the locking lever at the trailing or uppermost side of the cap C. The slot 23 is of sufficient width to enable the locking levers to move freely along the same, but prevents the caps from rotating about their own axes in the chute 12. With the locking levers positioned in this manner, the caps cannot become overlapped because the locking levers are, in effect, interposed between the successive caps. Hence, the caps cannot become jammed in the chute. As is diagrammatically shown in Figures 2 and 3, a gate or damper element 24 is provided adjacent the lower end of the chute 12 to normally hold the lowermost cap in the position illustrated in Figure 1.

The cap turning mechanism includes a plate 30 secured to blocks such as 31 which, in turn, are fixed to a rail 32 extending above the conveyors 10 and 12. A second and smaller plate 33 is positioned in the same plane as the plate 30, plate 33 being supported upon a rail 34 suitably supported above the conveyors. Referring

to Figure 2, it will be observed that the opposed edges 32a and 34a of the rails 32 and 34 serve to guide the bottles and prevent them from rotating. As is also shown in Figure 2, the two plates 30 and 33 have their opposed edges 35 and 36 aligned with the edges of the slot 23 of the cap applying chute 12 so that, in effect, they form a straight slot 37 which is a horizontal prolongation of the chute slot 23. However, as indicated at 38, the edge 35 of plate 30 is convexly arcuate at a point intermediate its length, this arcuate portion being concentric with the axis of an upstanding stud 39 fixed to the rail 32. The second plate 33 is of less length than plate 30 and its outfeed end is arcuately concave to conform to the portion 38 of plate 30.

As is best shown in Figures 1 and 2, the stud 39 is fixed in an aperture in the rail 32 of the capping apparatus and extends upwardly through the rail and plate 30. Between rail 32 and plate 30, the stud 39 has the circular and disc-like cap turning element 13 rotatable thereon. A spring 43 surrounds the stud 39, the lower end of the spring bearing on a washer 44 mounted on disc 13 and rotatable in an aperture in the plate 30. The upper end of spring 43 contacts with a cap nut 45 threaded to the upper end of the stud. The tension exerted by spring 43 upon the disc 13 is insufficient to prevent the disc being turned by the movement of containers as hereinafter described. However, the spring prevents the disc from over-traveling with a container.

Disc 13 is provided with a plurality of radially extending and equidistantly spaced recesses designated 13a, 13b and 13c. While the recesses are substantially U-shaped in plan, their walls are vertically straight and parallel with the axis of the disc. However, as best shown in Figure 3, a narrow ledge 50 extends about the lower edge of the walls of each recess. This ledge is adapted to loosely engage a shoulder s on each bottle. Above the ledge 50, the opposite walls 51 and 52 of each recess are so spaced that they will accommodate but closely engage the greatest diameter of a cap C, which is usually at the lower portion of the cap. At this portion of the cap, upwardly bent and spaced tongues t (Figure 3) partially enclose the locking wire which there encircles the cap and the edges of these tongues provide serrations which will be frictionally engaged by the recess walls above the ledge 50.

The inner and curved wall portion 53 of each disc recess is curved on a radius closely corresponding to that of the greatest diameter of the cap. The portion of the ledge 50 extending about the curved portion is curved on a radius very slightly larger than the radius of the bottle shoulder s. As is illustrated in Figure 4, the radial depth of each recess is such that a cap may lie entirely within it. The disc is of such vertical depth that the plate 30 will be slightly spaced above the caps C moving with the disc. Also, the diameter of disc 13 is such that its periphery conforms to the concavely curved outlet edge portion of plate 33. The convexly curved portion 38 of plate 30 is spaced inwardly of the disc periphery so that a locking lever L of the cap may freely move between the opposed edges of the plates 30 and 33 and without contacting with such edges.

The sealing head 15 may be similar to that disclosed in said Mair patents and will include a locking lever operating element 17. The head 15

is positioned immediately adjacent the outfeed end of the plate 30. In addition, as is shown in Figure 1, the capping head 15 moves along a vertical line which is within the length of the stationary and container supporting plate 14 so that it can seal containers while the latter are on plate 14. Rail 34 will be notched to clear downward movement of head 15 and element 17.

In the operation of the above described apparatus and mechanism, bottles or other containers 11 are placed upon the infeed conveyor 10 with the flat sides 11a of the bottles parallel with their line of movement as indicated by the dot and dash lines of Figure 2. The bottles will normally be placed upon the conveyor with their narrower surfaces in contact. The edges 32a and 34a of the rails 32 and 34 will engage the necks of the bottles to hold them in a straight line and prevent them from turning. If necessary, other and lower rails may also be provided for these purposes. When a bottle reaches the position illustrated in solid lines in Figure 1, it will withdraw the lowermost cap C from the chute against the restraining action of the gate or damper 24 so that the cap will fall to a horizontal but loose position on the mouth of the bottle. The pressure of the succeeding bottles moving with the conveyor 10 will cause the bottle and cap to move beneath the plates 30 and 33, with the locking lever L of the cap extending upwardly through the slot 37 as shown in Figure 2. At this time, a recess of the disc 13, for example, the recess 13a, will be at the position illustrated in Figure 2. In this position, the leading side wall 51 of the recess will lie across the outfeed end of the straight portion of slot 37.

With bottle 11 and cap C in the position illustrated in Figure 2, and with the disc 13 positioned as there shown, the continued forward movement of the container in a straight line will cause the cap C to exert pressure upon the leading edge 51 of the recess 13 to thereby rotate the disc 13 in a counter-clockwise position as viewed in Figure 2. However, the frictional engagement between the wire-encircled portion of the cap C and the surfaces of the recess 13a will cause the loose cap C to rotate relatively to the bottle mouth in a counter-clockwise direction, while the cap moves linearly from the Figure 2 position to that of Figure 4. The curvature at the outfeed end of the slot 37 concentric with the axis of stud 39 permits this rotation of the cap in that it provides a path for the swinging movement of the locking lever L.

By the time that the bottle has reached the position illustrated in Figures 3 and 4, the cap will have rotated 90° upon the bottle, even though the disc 13 has only rotated 60° during its movement from the Figure 2 position to that of Figure 4. The fact that the cap rotates bodily about its own axis to a greater extent than the disc 13 rotates about stud 39 is due to the frictional effect of the disc 13 upon the cap C, in combination with the forward or linear movement of the cap with the bottle.

After the cap and bottle have reached the position shown in Figures 3 and 4, and although the bottle and cap will then still act upon the disc 13 to carry it around to the position occupied by the recess 13c in Figure 2, nevertheless, the cap will no longer rotate upon the bottle because at that time the bottle will be moving away from the disc. Should the cap tend to turn further at this time, its locking lever will engage the straight edge 30a of plate 30, so that further rotation of

the cap will be prevented. As a result, the locking lever and cap will remain in the position illustrated in Figures 3 and 4, i. e., with the locking lever L extending downwardly along a line intersecting the flat side 11a of the bottle.

Because the cap and bottle leaving disc 13 will move recess 13a to the position occupied by recess 13c in Figure 2, recess 13b will be in a position to engage the cap of the next bottle.

The continued pressure of the succeeding containers upon the container 11 will thereafter move it beneath the sealing head 15 when its mouth portion will contact with the trip 16 to cause the capping head to descend as described in said Mair patents to bring the usual top gasket or sealing disc of the bottle into engagement with the lip of the bottle so that it will be substantially sealed upon the bottle. Immediately thereafter, the shoe 17 will move downwardly to engage the upstanding locking lever L and move it downwardly to a locking position as is also described in the Mair patents. This will cause the cap locking wire to contract and thereby lock and further seal the cap to the container. After the capping head 15 and shoe 17 have lifted, the bottle will be pushed on to outfeed conveyor 18.

It will be observed that the type of caps mentioned herein, i. e., caps of the type shown in said Williams Patents Nos. 1,743,945, and 1,214,734 may be considered as slip-type caps in that they are moved to container sealing position by straight downward movement of the caps upon the containers. The invention is useful with other types of caps of the slip type and which can be frictionally engaged by an element such as the element 13.

The terminology used in the specification is for the purpose of description and not of limitation, the scope of the invention being indicated in the claims.

I claim:

1. In an apparatus of the class described, means to move a container device along a predetermined path, a closure device applying means above said container device moving means to position a slip-type closure device in closing relation upon a container device which is positioned in said path, and means to then rotate one of said devices a predetermined extent with respect to the other and without varying their relative position lengthwise of the container device axis so that they will be in a predetermined circumferential alignment.

2. In an apparatus of the class described, means to move a container device along a predetermined path, a closure device applying means above said container device moving means to position a slip-type closure device in closing relation upon a container device positioned in said path, means to then rotate one of said devices a predetermined extent with respect to the other so that they will be in a predetermined circumferential alignment, and means to move one of said devices axially with respect to the other so that they will be in sealing relation.

3. In an apparatus of the class described, a straight line conveyor to move containers having caps loosely applied thereto, a horizontally arranged disc element rotatable about a vertical axis which is positioned laterally of the path of containers with said conveyor, said disc including a recess adapted to laterally engage a cap so that movement of the cap with a container will rotate said disc about its axis and the engage-

ment of the recess and cap will rotate the latter with respect to the container.

4. An apparatus of the character described in claim 3 wherein the disc is rotatable through 360° about its axis and includes a plurality of recesses adapted to engage caps on successive containers.

5. In an apparatus of the class described, means to move a container along a predetermined path, an inclined cap chute positioned above said path and arranged to support a cap in position for removal by a container moving beneath the chute, a horizontally arranged disc element provided with a plurality of peripheral recesses each conforming to the diameter of the caps applied by said chute, said disc normally being positioned so that an advancing cap will engage and be encircled by a recess in said disc and being rotatable by the advancing containers to thereby frictionally engage the caps to rotate them with respect to the containers.

6. In an apparatus of the class described, a straight line conveyor to move containers having caps loosely applied thereto, an element rotatable about a vertical axis which is positioned laterally of the path of containers with said conveyor, said 25

element including means adapted to laterally engage a cap so that movement of the cap with a container will turn said element about its axis and the engagement of the recess and cap will rotate the latter with respect to the container.

MILO BURNELL.
